UNITED STATES PATENT OFFICE.

HENRY L. FRANKLIN AND CHRISTOPHER C. BRAGG, OF HUNTINGTON, WEST VIRGINIA.

OVEN-SHELF.

1,244,440.

Specification of Letters Patent. Patented Oct. 23, 1917.

Application filed April 21, 1917. Serial No. 163,638.

To all whom it may concern:

Be it known that we, HENRY L. FRANKLIN and CHRISTOPHER C. BRAGG, citizens of the United States, residing at Huntington, in the county of Cabell and State of West Virginia, have invented new and useful Improvements in Oven-Shelves, of which the following is a specification.

Our invention relates to oven shelves and has for its objects; first, to provide an oven shelf which may be easily and quickly detached from its mountings in the oven, and secondly, to provide an oven shelf having movable mountings in the oven, said shelf having connections with a movable door of the oven whereby the shelf is properly positioned in the oven when the door is closed, the opening of the doors serving to withdraw the shelf from the oven and to properly position the same for convenient manipulation and inspection of articles on the shelf.

With these and other objects in view which will be hereinafter fully described and particularly pointed out in the claims, the invention consists in the novel construction and arrangement of parts illustrated in the accompanying drawings forming a part of this specification, in which:—

80 Figure 1 is a front elevation of an oven embodying our invention with the door thereof in open position.

Fig. 2 is a vertical sectional side elevation of the mechanism illustrated in Fig. 1, with the door closed.

Fig. 3 is a view in oblique perspective of the shelf.

Like characters of reference indicate like parts in the various views.

40 In the drawings 1 designates generally an oven comprising side walls 2, a back wall 3, a bottom wall 4, and a door 5 constituting the front wall thereof, and having its lower edge hinged to the oven structure, as designated at 6, to swing upon a horizontal axis. A latch 7 of usual construction is provided on the oven structure and adapted to engage the upper edge of the door to hold it closed. A pair of arms 8 are provided, each arm being pivoted to its corresponding side wall 2 at a point adjacent the rear lower corner of the wall. Each arm has a series of holes 9 formed therein along the length of the same.

50 A pair of spaced extensions 10 are formed upon the inner side of the door, and a series of holes 11 are formed in each of said exten-

sions along the length thereof. A shelf 12 is provided having extensions 13 at the corners thereof and adapted to engage holes in the corresponding arms 8 and extensions 10. 60 The shelf 12 comprises two members 14 having their corresponding sides hinged together, as designated at 15, stops 16 being provided on said shelf members whereby they are prevented from swinging beyond 65 their common plane in one direction. In placing the shelf upon its mountings in the oven, which comprise the holes in the arms 8 and the extensions 10, the members 14 are swung upon their hinged connection 15 until 70 the shelf will pass between the arms and said extensions. The extensions 13 are then moved into their respective holes on said arms and extensions by swinging the shelf members toward their common plane. This 75 movement projects the extensions 13 into the respective holes and when the shelf members lie in their common plane said extensions properly engage the holes for supporting the shelf. The stops 16 prevent the shelf 80 from swinging beyond their common plane in the other direction and the shelf is thus retained upon its mountings in the oven. The series of holes upon the arms 8 and the extensions 10 serve to allow vertical adjust- 85

ment of the shelf upon its mountings in the oven. Stops 17 are provided on the side walls of the oven and are adapted to engage the arms 8 when they are swung to their outermost position to prevent the arms 90 swinging forward too far.

When the door is closed, it will be noted by referring to Fig. 2, that the shelf is properly positioned within the oven and lies in a horizontal plane. As the door is opened the 95 shelf is drawn outwardly with the door, and as the door is opened moved downwardly also, so that when the door reaches its lower position and is stopped by the arms 8 engaging the stops 17 the shelf is in a comparatively low position and is projected partially out of the oven. In this position all parts of the shelf may be easily reached and inspected. When the door is closed again the oven is raised into its proper position.

Having thus fully described our invention, we claim:—

1. In a device of the character described the combination with a receptacle, of a door hinged to said receptacle, a shelf adapted for movement in said receptacle, arms mounted in said receptacle and having holes

- 2
- formed along the lengths thereof, a pair of spaced extensions formed on the inner side of said door and extending longitudinally thereof and having holes formed along 5 the lengths thereof, a shelf adapted for movement in said receptacle, means on said shelf for engagement with corresponding holes of said arms and extensions, and means on said shelf for disengaging said 10 first mentioned means from the engaged hole.
2. In a device of the character described the combination with a receptacle, of a door hinged to said receptacle, a shelf 15 adapted for movement in said receptacle, arms mounted in said receptacle and having holes formed along the lengths thereof, a pair of spaced extensions formed on the inner side of said door and extending longitudinally 20 thereof and having holes formed along the lengths thereof, means on said shelf for engagement with corresponding holes of said arms and said extensions, said shelf being foldable to disengage said means 25 from the engaged holes.
3. In a device of the character described the combination with a receptacle, of a door hinged to said receptacle, a shelf adapted 30 for movement in said receptacle, arms mounted in said receptacle and having holes formed along the lengths thereof, a pair of spaced extensions formed on the inner side
- of said door and extending longitudinally thereof and having holes formed along the 35 lengths thereof, said shelf comprising two members having their corresponding sides hingedly connected and having stops formed thereon adapted to prevent said members from swinging beyond their common plane in one direction, and projections formed on 40 said shelf members adapted to engage corresponding holes of respective arms and extensions when said shelf members lie in their common plane.
4. In a device of the character described 45 the combination with a receptacle, of a shelf comprising two members having their corresponding sides hingedly connected together and having stops formed thereon adapted to prevent said members from 50 swinging beyond their common plane in one direction, projections formed on the sides of said shelf, and means in said receptacle for engaging said projections and supporting the shelf when said shelf members lie 55 in their common plane, said projections being disengaged from said means when said shelf members are positioned out of their common plane.

In testimony whereof we affix our signatures.

HENRY L. FRANKLIN.
CHRISTOPHER C. BRAGG
